LOOSE-LEAF STRUCTURE

John Schade, Holyoke, Mass., assignor to National Blank Book Company, Holyoke, Mass., a corporation of Massachusetts

Application February 25, 1939, Serial No. 258,377

11 Claims. (Cl. 129—8)

This invention relates to improvements in loose leaf structures for holding a pack or filler of loose leaf sheets. The improvements are disclosed in their preferred form as applied to a binder of the type shown in my prior Patent No. 1,990,136, of February 5, 1935. The features of the present invention have particular importance in improving the operation of the type of binder shown in said prior patent. Also, the arrangement of the various elements has certain advantages which will appear from the description and claims.

Since the construction and operation of the parts of the specific disclosure herein are in some respects quite similar to those fully described in my prior patent, I will only show them in a general way and confine the particulars and detailed description to the new features.

In the drawings:

Fig. 1 is a top plan view of the binder in closed position but with the covers broken away;

Fig. 2 is a view of the binder of Fig. 1 but with the parts in the reading position;

Fig. 3 shows the binder opened to its maximum and ready to be positioned to allow insertion or removal of sheets;

Fig. 4 is an enlarged detail view, taken on line 4—4 of Fig. 2, of the latching mechanism which ordinarily holds the binder in the reading position of Fig. 2;

Fig. 5 is an enlarged view on line 5—5 of Fig. 1 showing how certain of the parts are nested together;

Fig. 6 is a sectional view on line 6—6 of Fig. 1;

Fig. 7 is a sectional view on line 7—7 of Fig. 3;

Fig. 8 is a view of the parts of Fig. 7 moved to the position in which the sheets may be inserted or removed;

Fig. 9 is an alternate form of structure which may be used;

Fig. 10 is a detail sectional view on line 10—10 of Fig. 9;

Figs. 11 and 12 show a further variation of structure which may be used;

Fig. 13 is a view taken on line 13—13 of Fig. 11; and

Fig. 14 is a detail sectional view on line 14—14 of Fig. 4.

Referring to Figs. 3 and 7, the binder consists of flat back plates 5 and 6 with upstanding flanges along their outer long edges to which flanges are attached binding prongs 7 and 8 and covers 9 and 10. In addition, plate 5, for the sake of appearance, is provided with the decorative backing strip 11. Along its narrow edges, this

plate 5 has a pair of guide members 12 and 13 each of which is in the form of an angular flange secured to the plate as by the rivets 14. The upstanding arms of these flanges or guide members 12 and 13 end in rebent sections 15 and form 5 guideways to receive the upstanding arms of a pair of angular flanges 16 and 17 which are similarly attached to plate 6. As is plain from Fig. 7, the flanges 16 and 17 have goose neck extensions 18 which protrude beyond the inner turned up 10 edge 19 of plate 6, and are pivoted as indicated at 18' directly to the tie bar 20 of equalizer mechanism consisting of said tie bar 20 and long and short levers 21 and 22 (see also Figs. 1, 2, 3 and 6). These gooseneck portions 18 are also provided 15 with slots 25 and rounded corners 26 so that the binder plates 5 and 6 may be positioned as in Fig. 8 simply by separating them to the position of Fig. 7 and then rotating them around the pivot 18' between the tie bar 20 and gooseneck extensions. In this last position the back plates 5 and 20 6 form an inverted V with the strip 11 on plate 5 resting against the turned up edge 19 of plate 6. As is explained in the earlier patent referred to, this general position is the one in which sheets 25 contained in the prong sets may be most conveniently inserted or removed.

On the other hand, with the parts positioned as in Fig. 7, the flat back plates 5 and 6 can be slid towards each other, the upstanding arms of 30 flanges 16 and 17 moving along the passageways provided by flanges 12 and 13 with the flat back plates parallel to each other and in overlapping relation.

During this lateral motion, the back plates 5 35 and 6 are constrained by the equalizer mechanism previously referred to as consisting generally of the tie bar 20, and long and short levers 21 and 22. As appears from Figs. 1, 3 and 6, the long arm 21 has a fixed pivot 30 at one end on plate 40 5 and at the other end a sliding pivot with tie bar 20, this last pivot consisting of a pin 31 which can slide along a slot 32 cut in the upper end of said tie bar. On the other hand, the short arm 22 is fixedly pivoted to the center of long arm 21 45 and the lower end of the tie bar by pins 33 and 34, respectively. In passing from the fully closed position of the binder, as shown by Fig. 1, to the reading position of Fig. 2, and finally to the fully 50 opened position of Fig. 3, this equalizer mechanism works like lazy tongs to positively assure that the upstanding arms of flanges 16 and 17 cooperate smoothly with the passageways provided by flanges 12 and 13.

Specifically comparing Figs. 1 to 3, when the book back is in closed position (Fig. 1) the pivots of the tie bar 20, long arm 21, and short arm 22 are all in the same longitudinal plane with the pin 31 at the outermost end of the slot 32. As soon as the user starts to move the book to its reading position (Fig. 2), the tie bar 20 moves laterally and the pin 31 starts to move inwardly of the slot 32 so that the pins 31 and 34 are constantly in a longitudinal plane parallel to the long edges of the flat plate 5. As the separation of the plates 5 and 6 is continued beyond the reading position, pins 31 and 34 stay in the same longitudinal plane parallel to the long edges of the plate 5, and the plates are stopped at their fully spread position of Fig. 3 when pin 31 reaches the inner end of slot 32.

A further description of this equalizing function is contained in the earlier patent referred to 20 and this action will not therefore be gone into in further detail.

As is explained in the earlier patent, this type of binder is stored or filed with the parts in the back-closed position shown by Fig. 1, while its 25 normal reading position is that of Fig. 2—that is, with the plates 5 and 6 displaced laterally. The position of Fig. 8 is provided for primarily to facilitate changing sheets. To insure that the book will not inadvertently be opened beyond the 30 reading position, the latch shown in detail in Fig. 4 is used. As can be seen from that figure taken in conjunction with Figs. 1, 2 and 14, this latch consists of an L shaped member 39 with its long leg pivoted to the side of flange 17 and 35 its short leg overhanging the top edge of said flange. Clearance is provided between the member 39 and flange 17 for passage of the flange 13 attached to plate 5. The short leg of this latch member 39 terminates at its forward end in a 40 thumb piece 40 overlying a depression 41 in flange 17, and the forward end of the long leg extends beyond the thumb piece terminating in a toe 42. This toe 42 passes through a slot 43 in flange 17 and forms a stop for an abutment piece 44 formed 45 on the lower edge of the rebent portion 15 of flange 13. To open the book to the position of Fig. 8, the user separates the plates 5 and 6 to the position of Fig. 2, presses on the thumb piece 40 to move the latch downward (said latch being 50 frictionally pivoted to normally retain the position to which it is moved) so that the toe 42 clears abutment 44 and the thumbpiece lies in depression 41, and then separates the plates to the position of Fig. 3 when the back plates can be 55 pivoted as previously described. To again close the book, the plates are swung to the position of Figs. 3 and 7 and forced laterally together to the position of Fig. 1. As soon as the top edge of the rebent section 15 of flange 13 hits the thumb piece 60 40 in the latch 39, it will raise the latch to make it effective to stop the opening of the book at the reading position when the plates are again pulled laterally apart.

Referring now to Figs. 5, 7 and 8, when the 65 binder is being closed after insertion or removal of sheets, the plates 5 and 6 must first be positioned parallel to each other as in Fig. 7 before any lateral pressure is exerted or the flanges 16 and 17 will bind in the passageways provided by flanges 70 12 and 13. Therefore I form each gooseneck 18 with a toe 48 which protrudes as an extension of the gooseneck. As is apparent in Fig. 7, each toe is dimensioned to ride on the top of the lower part 75 of flanges 12 and 13 and to make its bearing with these surfaces when the plates 5 and 6 are paral-

lel and the top edge of flanges 16 and 17 are in contact with the under surfaces of the top of the U sections formed by the rebent portions 15 of the flanges 12 and 13. This arrangement determines that the flat plates are parallel and will therefore slide easily over each other. 5

Of course, the rebent portions 15 can be dimensioned so that in the absence of toes 48 the top edges of flanges 16 and 17 adjacent the gooseneck portions will abut the inner top surface of 10 the rebent portions when the plates 5 and 6 are parallel and thereby furnish a stop. With such an arrangement there would be a great deal of strain on the rebent portions with the structure shown. Therefore, by the use of the toe 48 the 15 strain due to careless closing is removed from the rebent portion 15 and it is thus enabled to retain its shape.

Referring to Fig. 5, this toe 48 in no way interferes with the closed position of the binder, for 20 the upstanding flange of plate 5 is slotted as indicated, and the toe 48 passes through this slot and may either rest against the cover 9 or, as indicated, be received by a recess cut in that cover.

Referring now to Figs. 1 to 3 and 6, certain 25 specific advantages of this particular equalizer mechanism will be pointed out. In the first place, the entire mechanism is contained between the inner edge of plate 6 and the upstanding flange of plate 5. Thus, the mechanism adds substantially no thickness to the back panel portion of 30 the binder.

Again, by using a short arm 22 and long arm 21 arranged as indicated and previously described, the mechanism can be folded to the position of Fig. 1 with all the pivot points located in a single longitudinal plane. If the short arm 22 were replaced by a long one similar to arm 21 and this arm pivoted to plate 5 at the upper end thereof, this pivot would intersect the plane of 40 arm 21 (see Fig. 6) and prevent that arm 21 from swinging to the position of Fig. 1. With this last arrangement, the opening and closing of the binder would be limited because of the limited motion of the equalizer mechanism. Also, if a 45 second long arm were used, tie bar 20 would necessarily have to be provided with a slot similar to slot 32 for the pin 34. This of course would introduce additional possibility of undesirable tolerances in the moving parts which might hamper 50 the operation of the equalizer mechanism.

Considering the above, it will be seen that the equalizer mechanism performs its function though its construction is extremely simple, and, for the purposes of my invention, is particularly 55 apt. On the other hand, recalling an earlier part of the specification wherein the function of the toes 48 in the gooseneck portions 18 was discussed those skilled in the art will realize that various modifications of the preferred form of my invention are possible. In the subsequent paragraphs, I will disclose a few other ways of practicing my invention which may occur to those who have been informed of its principles by a reading 60 of the foregoing description.

As was pointed out earlier in the specification, the rebent portions of the flanges 12 and 13 cannot, because of the strain put on them, be satisfactorily used in conjunction with the top edges of flanges 16 and 17 to provide for the sole means 70 to stop the plates 5 and 6 in parallel relation when the book is closed from the position of Fig. 8 to that of Fig. 7. One solution of this is as follows. The flange can be extended beyond the edge of the plate 5 so that the rebent portions 15 75

would overhang the flanges 16 and 17. However, something more is desirable because the overhang would interfere with the upstanding prong carrying flange on plate 6 in the closed position. In 5 Figs. 9 and 10, this difficulty is solved by the structure illustrated. The rebent portion 15 is made so that its internal channel is oversize and a slipper 50 placed over the gooseneck 18 between that member and the rebent portion. This slipper 10 is pivoted at 20' to the tie bar 20 and in turn the gooseneck portion is pivoted to the slipper at 50'. While the gooseneck portion 18 has no protruding toe as in the preferred form, the forward end of the gooseneck has a flattened surface 15 53 which, in the position of Fig. 9, serves as a bearing on the upper horizontal surface of the flanges 12 and 13. As that figure shows, the forward end of the slipper 50 has an arm 51 which bears on the top of the flanges 16 and 17 and this, 20 in combination with the flattened portion 53, will form a satisfactory stopping means to arrest the plates 5 and 6 in parallel relation. Comparison of the broken and full line positions of the flange 16 in Fig. 9 will make the stopping action of this 25 mechanism clear. Inasmuch as the slipper 50 is pivoted to the tie bar 20 and its heel 55 does not protrude beyond this bar, no special provision is necessary to allow for the complete closing of the book when the plates 5 and 6 are slid together 30 to the position of Fig. 1.

In the structure shown in Figs. 11 to 13, the slipper 58 which is pivoted to the tie bar 20 in the same manner as described above for slipper 50 has a longer heel 57 than that in Figs. 9 and 10, 35 and the gooseneck portion 18 has a sliding pivot provided by the pin 59 and slot 60. Also, the slipper is provided with a forwardly extending arm 62 which is arranged to contact the upper surface of the horizontal arm of flanges 16 and 17. With the plates 5 and 6 positioned ready to 40 rotate about pin 59 (see Figs. 11 and 13) said pin is located at the forward end of slot 60 and the stopping means is provided by the flattened portion 53 of the gooseneck 18 and the arm 62. Because of the length of the heel 57, this structure 45 is very strong and effective in performing the desired function.

When the plates 5 and 6 are being slid towards each other, the pin 59 first progresses to the end 50 of slot 60 and then the slipper 58 begins to move (see Fig. 12). At this time the vertical edge of the heel of the slipper is in line with the edge of the tie bar 20 so that, as with the previous form of mechanism, no special provision to accommodate the slipper is necessary in the completely 55 closed position.

As is evident from the preceding description, my invention represents a definite improvement in the loose leaf binder field for not only have I 60 been enabled by its application to produce an exceedingly neat and compact structure wherein the equalizing mechanism occupies substantially no more space than the necessary thickness of the back plates; but also this structure is much more 65 easily handled, particularly during the closing of the book, after new sheets have been inserted because of the provision of my novel stop mechanism for limiting the rotation of the back plates to their parallel position.

70 One of the main features of the invention is in the means provided to bring the parts at the book back into compact form and minimize the bulk at the back when the book is ready to be stored for use. Considering the means provided 75 in the back for the desired functional manipula-

tion of the book, it will be seen that they occupy little space. For example, the equalizer means is capable of collapsing into a narrow thin space; the part for bracing the telescoping halves is tucked away in a recess. Either one or both of 5 these provisions definitely results in the functions desired while using less book space than if these functions were performed in other ways.

Another feature of the invention is that the structure shown is not only exceedingly cheap to 10 manufacture but is so arranged that it will perform its function positively though submitted to rough and careless usage with the result that a cheaper product with a longer useful life is 15 obtained.

I claim:

1. In a binder of the class described, the combination of one short and two long bars pivoted together as an equalizer mechanism and collapsible for said bars to lie directly over one another, 20 a prong carrying back portion attached to one of said long bars for holding it permanently in right angle relation to the prongs on said back portion, a second prong carrying back portion in underlying and slidable relation to the first and to which one end of the other long bar is pivoted, 25 said two back portions when in nested relation having the bars of said equalizer mechanism lying directly one over the other in a narrow space 30 between the outer edge of one and the inner edge of the other of said back portions, whereby the nesting of the back portions with the equalizer mechanism in collapsed position avoids excessive width of the binder back.

2. In a binder of the class described, two prong carrying back portions, each of which has end flanges, one pair fitting into the other for sliding movements, one pair having overhanging portions to provide for pivoting said back portions, pivot means for the overhanging portions, 40 extensions on said overhanging portions to give extra leverage for stopping pivotal movement of the back portions in one direction when parallel and ready to slide together, recesses in one of the back portions to receive said extensions at the 45 end of their sliding movement in nesting the back portions.

3. A loose-leaf structure consisting of two back plates, complementary guide means on the plates for holding the plates while in overlapped and 50 slidable relation, and equalizing means, operable by movement of said plates, adapted to maintain the sides of the plates parallel as they are moved to varying overlapped positions and to hold the plates in pivotal engagement when they are 55 moved out of overlapped relation, said equalizer means consisting of a combination of levers that at least in the collapsed position lies between the inner edge of one plate and outer edge of the other plate for the purpose described.

4. A loose-leaf structure consisting of two back plates, complementary guide means on the plates for holding the plates while in overlapped and 60 slidable relation, and equalizing means, operable by movement of said plates, adapted to maintain the sides of the plates parallel as they are moved to varying overlapped positions and to hold the plates in pivotal engagement when they are 65 moved out of overlapped relation, the guide means on one of said plates having additional means 70 adapted to limit the pivotal movement of said plates in one direction to the parallel position of said plates when the plates are in non-overlapping position.

5. A loose-leaf structure consisting of two back 75

- plates, complementary guide means on the plates for holding the plates while in overlapped and slideable relation, and equalizing means, operable by movement of said plates, consisting of a combination of flat levers adapted to maintain the sides of the plates parallel as they are moved to various overlapped positions and to hold the plates in pivotal engagement when they are moved out of overlapped relation, the guide means on one of said plates having additional means adapted to limit the pivotal movement of said plates in one direction to the parallel position of said plates when the plates are in non-overlapping position.
6. The structure of claim 5 with said additional means consisting of a member protruding from the guide means on one plate and resting on a horizontal part of the binder and overlying the other plate when said plates are parallel.
7. A loose-leaf structure consisting of two back plates, complementary guide means on the plates for holding the plates while in overlapped and slideable relation, and equalizing means, operable by movement of said plates, consisting of a combination of flat levers adapted to maintain the sides of the plates parallel as they are moved to varying overlapped positions and to hold the plates in pivotal engagement when they are moved out of overlapped relation, the guide means on one of said plates having a protruding member resting on a horizontal part of the binder and overlying the other plate when said plates are parallel and in pivoted relation and nested within a recess in said binder beyond the edge of said guide means when the plates are overlapped to their maximum, all for the purpose described.
8. A loose-leaf structure consisting of two rectangular back plates, complementary guide means on the plates along the upper and lower edges for holding the plates during overlapped and slideable relation, and equalizing means, operable by movement of said plates, adapted to maintain the sides of the plates parallel as they are moved to varying overlapped positions and to hold the plates in pivoted engagement when they are moved out of overlapped relation, said equalizer means consisting of a tie bar with its long axis parallel to the side edges of the plates and pivoted about this axis at each end to the guide means associated with one of the plates, a long lever arm pivoted at one end to the tie bar adjacent one end of said tie bar, and at the other end, to an outer corner of the other plate at the end of said plate which is remote from said pivot on said tie bar, one of said long lever arm pivots being fixed and the other sliding, and a short arm fixedly pivoted to the midpoint of the long arm and to the other end of the tie bar all for the purpose described.
9. A loose-leaf structure consisting of two flat rectangular back plates in overlapped relation, said upper plate having upstanding flanges at each end with gooseneck portions of the flanges extending beyond the inner side edge of said plate, said lower plate having complementary upstanding flanges at each end with a rebent portion under which said first mentioned flanges slide, equalizer mechanism, operable by movement of said plates, pivoted to said gooseneck portions and adapted to maintain the side edges of said plates parallel as they are moved to varying overlapped positions and to hold the plates

in pivotal engagement when they are moved out of overlapped relation, but with the gooseneck portions still within the rebent portions, each gooseneck portion having a protruding toe adapted to bear on a horizontal binder part when the plates are parallel all for the purpose described.

10. A loose-leaf structure consisting of two flat rectangular back plates in overlapped relation, said upper plate having upstanding flanges at each end with gooseneck portions of the flanges extending beyond the inner side edge of said plate and each having a flat surface along its lower edge, a U-shaped slipper pivoted in inverted position over the top edge of each of said gooseneck portions and having at the forward end an integral arm extended and overlapping the upper edge of the flange back of the gooseneck portion with the heel of said slipper substantially flush with the forward end of said gooseneck portion, said lower plate having upstanding flanges at each end with rebent portions under which said slippers slide, equalizer mechanism, operable by movement of said plates, pivoted to said slippers and adapted to maintain the side edges of said plates parallel as they are moved to varying overlapped positions and to hold the plates in pivotal engagement when they are moved out of overlapped relation but with the heels of the slippers still within the rebent portions, said flat portions of said goosenecks being adapted to bear on a horizontal binder part on said lower plate and said extended arms of said slippers to bear on said flanges on said upper plate when the plates are parallel, all for the purpose described.

11. A loose-leaf structure consisting of two flat rectangular back plates in overlapped relation, said upper plate having upstanding flanges at each end with gooseneck portions of the flanges extending beyond the inner side edge of said plate and each having a flat surface along its lower edge, a U-shaped slipper pivoted in inverted position over the top edge of each of said gooseneck portions and having at the forward end an integral arm extending and overlapping the surface of said upper plate back of the gooseneck portion, said lower plate having upstanding flanges at each end with rebent portions under which said slippers slide, equalizer mechanism, operable by movement of said plates, pivoted to said slippers and adapted to maintain the side edges of said plates parallel as they are moved to varying overlapped positions and to hold the plates in pivotal engagement when they are moved out of overlapped position but with the heels of the slippers still within the rebent portions, said flat portions of said goosenecks being adapted to bear on a horizontal binder part on the lower plate and the extended arms of the slippers to bear on a horizontal part of said upper plate when the plates are parallel in their non-overlapping position, the pivots between the slippers and gooseneck portions each being in the form of a pin and horizontal slot with the pin in the pivoted position of the plates being located at the end of its slot nearest the extended arm of the slipper, whereby the heel of the slipper extends beyond the end of the gooseneck portion and a substantial distance under the rebent portion, all for the purpose described.

JOHN SCHADE.
